FLAKE ICE MAKING MACHINE AND WATER DISTRIBUTOR FOR USE THEREIN

William E. Lauterbach, Chicago, Ill., assignor to Akshun Manufacturing Company, Chicago, Ill., a corporation of Illinois

Application May 14, 1953, Serial No. 354,931

12 Claims. (Cl. 62—106)

My invention relates to an improved flake ice making machine and to a water distributing mechanism for use therein.

Flake ice making machines are intended to manufacture ice in dry flaked condition suitable for preserving food. For this purpose the machine should be inherently sanitary and easily cleaned. Also, since the machine is frequently used on an intermittent basis the unit should be capable of starting without freezing on one hand or splashing on the other hand. The machine should, in addition, be capable of operating without clogging from contaminations or from the formation of ice.

In one form of flake ice making machine, water is flowed on the inner face of a refrigerated cylinder to form ice thereon. A rotor carrying knives or other suitable harvesting means rotates within the cylinder to dislodge ice along a moving element of the cylinder. The resultant dislodged ice falls in flakes into a suitable ice collecting container.

In accordance with the present invention, the water is flowed on the upper edge of the freezing cylinder by an umbrella-like cap or water distributing pan unit carried by the rotor and extending to a lip closely adjacent the wall of the freezing cylinder. The cap has a hub portion that seats on the rotor and a wall outboard of the hub to define a water storage container. Water flows over the wall to cascade down the umbrella or conical part to discharge at the face of the freezing cylinder. The umbrella part of the cap has a fence extending about the region over the ice harvesting means to arrest water flow thereover. In accordance with further features of the present invention, the various parts of the mechanism are periodically wiped to assure production of dry flake ice and to arrest the growth of ice deposits.

It is, therefore, a general object of the present invention to provide an improved flake ice making machine.

Further, it is an object of the present invention to provide an improved flake ice making machine wherein the ice is not contaminated with water either during normal operations or during start up or shut down.

Additionally, the objects of the present invention include the provision of an improved flake ice making machine that is sanitary, easily disassembled for cleaning, free from freezing, characterized by a uniform water supply to the freezing cylinder, and inherently simple in structure and in operation.

Still another object of the present invention is to provide an improved flake ice making machine in which the growth of ice deposits is prevented by periodic wiping action.

The novel features which I believe to be characteristic of the present invention are set forth with particularity in the appended claims. My invention itself, however, both as to its construction and as to further objects and advantages thereof will best be understood by reference to the following description taken in connection with the accompanying drawings, in which:

Figure 1 is an axial cross-sectional view with parts in

2

elevation of a flake ice making machine constructed in accordance with the present invention;

Figure 2 is an enlarged fragmentary portion of Figure 1 taken along section 2—2, Figure 1;

Figure 3 is a view in perspective of the water distributor of the mechanism of Figure 1;

Figure 4 is a cross-sectional view through axis 4—4, Figure 3;

Figure 5 is an enlarged axial fragmentary cross-sectional view showing an alternate support for the water distributing mechanism; and

Figure 6 is a cross-sectional view through axis 6—6, Figure 5.

There is shown in Figure 1 an evaporator cylinder 10 having an inner wall 10a and an outer wall 10b defining an annular space in conjunction with the bottom ring 10c and the top ring 10d. Refrigerant 12 is supplied to the annular space thus formed by suitable means (not shown) and evaporates therein to maintain the inner wall 10a below water-freezing temperature. As is described in further detail hereafter, water is flowed onto this surface and the resultant ice dislodged to form ice flakes.

The freezing cylinder 10 is suitably supported by the frame 14 which has a series of radially extending spider arms 14a which terminate in a housing 14b at their center portions. This housing may be any suitable thrust bearing support housing. In the particular form shown, it carries a sleeve bearing liner 16a and a thrust bearing 16b, which in turn support the rotor 18.

The rotor 18 consists of a center shaft 18a which is sustained in vertical position by the upper sleeve bearing 20. This bearing is supported by the roof 22 carried by the freezing cylinder 10. This roof has a suitable access door 22a and may, if desired, include suitable elements (not shown) to permit the ready disassembly of the unit. The shaft 18a has a splined socket part 18b which receives the splined shaft 24a of the speed reducer 24 which is driven by motor 26. This mechanism turns the rotor at a very low rate to harvest or dislodge the ice as described in further detail hereafter.

Shaft 18a carries a radially extending vertical plate 18c as is shown in Figures 1 and 2. This plate is welded to the shaft as shown and terminates in a vertical edge spaced from the inner jacket 10a. At its outer end, this plate threadedly receives a plurality of bolts 28a which support the knife-defining bars 28. The bolts 28a are loosely received by the bars 28 so that these bars may be moved to a limited extent in the radial direction to provide the most effective clearance between the knives and the inner face of the evaporator 10. This adjustment is facilitated by the use of adjusting bolts 29a which are threadedly received in the support bar 29, the latter being welded to the plate 18c. Set nuts 29b prevent loosening of the bolts 28a.

The blades 28b are defined by the bar 28. This bar is of thickness corresponding to the desired circumferential extent of the blades and is of material suitable for the blades. The individual blade elements 28b are formed by milling out the bar 28 to form the separate blade blanks and then machining the outer edges of the individual blade blanks as required to form the desired ice harvesting edges. Preferably, the blades are given a slight tilt so that they tend to lift the ice and urge the rotor downwardly.

A pair of vertically spaced arms 30 are affixed to plate 18c by the bolts 30a, these being threadedly received in plate 18c. The arms 30 are bolted or otherwise attached to the vertically extending bar 32, which carries a flexible wiper or squeegee member 33. This squeegee bears against the face of the inner jacket 10a to wipe the freez-

ing surface dry in advance of the knives 28b and thus assure completely dry ice.

Water is flowed onto the inner face of inner wall 10a by the cap or water distributing pan shown generally at 34. This cap consists of a central hub 36, Figures 1 and 2, which seats slidably on the shaft 18a and rests on the annular shoulder 18d formed in the upper part of that shaft. The hub 36 receives an annular bottom plate 35, Figure 1, which has an opening 35a through which the lock pin 36 extends. This pin is received in a suitable vertical bore 18e in the plate 18c to anchor the pan 34 for rotation with shaft 18. The pin 36 is held in vertical position by the tab 36a which has a suitable opening to receive the pin.

The cap 34 has a conical umbrella portion 38 which extends radially downwardly and outwardly, as shown. The cap extends with little or no downward tilt within the confines of the cylindrical wall 40 and then tilts downwardly at a relatively small slope. At its radially outward extremities 38a the conical portion 38 of the cap has a region of sharper slope which terminates at lip 38b which is closely spaced to the inner surface of the inner wall or jacket 10a. The conical or umbrella portion 38 forms an annular throat of small thickness or cross-sectional area with respect to the inner face of the inner wall 10a and the inner face of insulating gasket 42 which is contiguous with the inner face of wall 10a. Gasket 42 is of neoprene or other suitable heat insulating material.

The cylindrical wall 40 has a series of notches 40a which extend downwardly from its upper lip, as shown. The lowermost reaches of these notches are at a common elevation above the base of the wall as shown. Water supplied to the container formed by the wall 40 overflows over the bottom edges of these notches which act as weirs and thence flows to the conical faces of the umbrella part 38. Water thus flows downwardly and radially outwardly in expanding streams to the small annular gap between inner wall 10a and the lip 38b to form ice on the inner face of wall 10a.

The water flow onto the wall 10a is interrupted in the region adjacent the knives 28b. This interruption is achieved by the generally triangular walls 44, Figure 3, and by the arcuate wall 45. Together these walls form a fence through which the water cannot pass and extending entirely about the region of knives 28b. The wall 45 is preferably formed as an integral portion of the cylindrical wall 40. Walls 44 are preferably welded to the wall 40 on their vertical portions and to the edges 38c of the umbrella portion 38 along their sides. It will be observed that water flowing through the notches 40a cannot flow in any circumferential direction so as to fall into any part of the segmental space defined by walls 44, 45, and 44, and the inner face of wall 10a. Thus the fall of water over the freezing surface is arrested prior to the time the knives 28b harvest the ice. The flow continues to be cut off until some time after the knives have traversed each point on the face of wall 10a, thus assuring production of dry ice uncontaminated by water flow. Since the squeegee 33 wipes the ice dry in advance of the knives 28b, the ice is dry and well below freezing temperature before it is harvested.

A deflector 46, Figure 1, in the form of a fragment of a cone is positioned below the knives 28b and is supported by arms 48, 48a, and 48b, from the plate 18c. These respective arms are bolted or otherwise secured to each other. Deflector 46 is positioned immediately below the knives so that the ice dislodged by the knives strikes the deflector and is deflected inwardly to fall in flakes into a suitable basket (not shown) provided for this purpose. Dropping flakes are shown at I, Figure 1. Water dripping from the wall 10a falls freely and thus drops into the annular gutter G, defined by the cylindrical support frame 14, the annular bottom plate 50, and the cylindrical inner member 50a. A suitable drain (not shown) is provided for this gutter.

Water is supplied to the container defined by wall 40 by the use of a suitably mounted stationary pipe 60, Figure 1. This pipe is supplied with water by suitable means (not shown) to achieve the desired total water flow onto the face of the inner wall 10a. Preferably some of this water is recirculated from gutter G. As shown in Figure 3, the lower part of wall 40 has a single opening 40b. This hole permits the water containing space formed by wall 40 to drain completely when shut down occurs, so that when the unit is subsequently started only new, fresh water is used. This hole is made sufficiently small so that the normal operation of the machine is not affected.

The above described flake ice making machine is characterized by a highly uniform water flow onto the inner face of wall 10a. This water flow occurs without splashing and without ripples and is uniformly distributed over the face of the wall. As a consequence a thin uniform sheet of water is made available for freezing into ice flakes, which are accordingly of uniform thickness and all have a full opportunity to freeze to a complete dry state before the flake ice harvest means dislodges them from the wall 10a. Since the flow of water onto the umbrella portion 38 of the cap 34 is controlled by the weir action of the wall 40 and by the rate of water input through pipe 60, a highly uniform water supply is achieved. The relatively long distance over which the water flows down the conical face 38 causes the water, which flows over the wall 40 in rivulets, to merge and form a circumferentially uniform sheet by the time the outer extreme of the umbrella portion 38 is reached.

The rather gradual slope of the portion 38 of the cap 34 aids in creating the circumferentially uniform water flow, since the water can flow in the circumferential direction much more easily with the cone of small slope. The portion 38a, having a greater slope, tends to impart great velocity to the water flow and, in addition, forms a throat 39, Figure 1, which actually fills with water during normal operation of the machine, although it is not essential that this action occur. This is due to the small radial extent of this throat, which in a machine actually constructed was made .060 inch.

Moreover, the slots 40a and the slope of unit 34 minimize the effects of machine tilt since small degrees of tilt do not alter the water flow over them. It is accordingly unnecessary to level the machine of the present invention with the same degree of exactness as has been heretofore required. It will also be noted that the substantial slope of the under side of the portion 38a of the water distributor prevents any tendency of the water to travel radially back or inwardly on the under side by reason of capillary attraction. This prevents ice contamination by such water.

The machine above described has been found to be very easily cleaned and free from clogging. The interior can best be cleaned by lifting the pin 36 and rotating the water distributor cap to enable the user to reach or climb down into any part of the machine.

The machine of the present invention has proven considerably more effective than machines in which water is supplied by orifices. These inherently drip during start up and shut down because the orifices produce a spray only when operating with the requisite head. The resulting drip tends to fall into the ice and thus contaminate it with water. Also, orifices clog easily and are difficult to clean.

It will be noted that the squeegee 33 bears on—and hence wipes—a complete element of the inner face 10a. Thus the entire vertical extent of the face 10a is wiped clean at a fixed time before the knives arrive. This assures a uniform degree of dryness of the ice even though some time is required for the water to flow from the top edge of the face 10a down to the bottom. In the absence of the squeegee, the ice would have varying degrees of dryness before harvesting.

The trailing face of the plate 18c receives a bent verti-

cal plate 70 which receives a somewhat heavier plate 70a at its outer extreme. Plates 70 and 70a coact with the plate 18c to form a vertical chute down which the harvested ice flakes fall. This chute minimizes any tendency of the ice flakes to fly about and fall into gutter G.

I have discovered that ice crystals tend to grow at the junction of the inner jacket 10a and the insulating gasket 72, located at the base of the machine. This ice formation requires cleaning with the consequent machine outages and inconvenience. This cleaning is rendered unnecessary by the wiper arm 74 attached to the lower edge of the knife-bar 28. This arm extends to proximity with the gasket 72 and wipes all excess ice crystals which form thereon. Since this wiping action occurs once for each rotation of the shaft 18, it occurs periodically at frequent intervals and the ice crystals never have an opportunity to build up greatly.

The deflector 46, which also tends to have accumulations of ice is likewise wiped by the fixed radial horizontal bolt 76 and by the tilted bar 78, the former being attached to the base plate 14c of the support frame and the latter being attached to the spider arm 14a. When the deflector 46 travels past bolt 76 and bar 78, most of its face is wiped free of ice and any upwardly extending ice formations are dislodged. This action—which occurs once each time the rotor rotates—prevents ice accumulation on the deflector.

Figures 5 and 6 show an alternative method of mounting the cap 34. With this arrangement the shaft 18 has a pair of ears 118a protruding above the shoulder 18d. The hub 136 of the cap 34 has a pair of slots to receive these ears, thus anchoring the cap 34 against rotation in relation to the shaft 18. A spring detent 190 is mounted in the shaft 18. When it is desired to free the cap 34 for rotation in relation to the shaft, this detent is pushed in and the cap 34 lifted until the detent rides in the groove 136a formed on the inner face of hub 136.

The pan or cap unit 34 may, if desired, be of cast or similar construction. It may also be of part cast construction and part fabricated. Moreover, if desired, the wall 44, Figure 3, may be made separate from the wall 40. If the pan or cap 34 is of cast construction, it is desirable to provide an annular notch under part 38a to give an upward tilt to the under surface and thus prevent any tendency of the water to travel radially inwardly as described above.

While I have shown and described a single embodiment of the present invention, it will, of course, be understood that many modifications and alternative constructions may be made without departing from the true spirit and scope thereof. I, therefore, intend by the appended claims to cover all modifications and alternative constructions falling within their true spirit and scope.

What I claim as new and desire to secure by Letters Patent of the United States is:

1. A flake ice making machine comprising in combination: a freezing cylinder; a rotor within the cylinder; knives on the rotor adapted to dislodge ice in flakes along an element travelling about the cylinder; and a water distributor located at the top of the cylinder and mounted on the rotor, the distributor comprising an umbrella portion sloping radially outwardly to a lip adjacent the face of the cylinder; a reservoir located towards the center of the umbrella and having a lip over which water flows onto the conical portion, the conical portion being fenced adjacent the said travelling element to arrest water flow to points near the knives.

2. A flake ice making machine comprising in combination: a freezing cylinder; a rotor within the cylinder; means on the rotor adapted to dislodge ice in flakes along an element travelling about the cylinder; a water distributor located at the top of the cylinder and mounted on the rotor, the distributor comprising an umbrella portion sloping radially outwardly to a lip adjacent the face of the cylinder and being fenced ad-

jacent the said travelling element to arrest water flow to points near the knives; and means to supply water to the top face of the umbrella portion.

3. A water distributing device for a flake ice making machine of the type in which ice dislodging means on a rotor travels about the face of a freezing cylinder to dislodge ice in flakes along an element travelling about the cylinder, the device comprising: a hub portion adapted to seat on the rotor; a conical umbrella portion extending radially outwardly and downwardly to a lip adjacent the face of the cylinder; means to distribute water over the face of the umbrella portion at points spaced from the lip; and a fence extending about the region of the element to arrest water flow to points adjacent the knives.

4. A water distributing device for a flake ice making machine of the type in which ice dislodging means on a rotor travels about the face of a freezing cylinder to dislodge ice in flakes along an element travelling about the cylinder, the device comprising: a hub portion adapted to seat on the rotor; a conical umbrella portion extending radially outwardly and downwardly to a lip adjacent the face of the cylinder; a cylindrical wall extending about the umbrella portion at points spaced from the lip and having a series of notches forming weirs; and a fence extending about the region of the element to arrest water flow to points adjacent the knives.

5. A water distributing device for a flake ice making machine of the type in which ice dislodging means on a rotor travels about the face of a freezing cylinder to dislodge ice in flakes along an element travelling about the cylinder, the device comprising: a hub portion adapted to seat on the rotor; a conical umbrella portion extending radially outwardly and downwardly to a lip adjacent the face of the cylinder; a cylindrical wall extending about the umbrella portion at points spaced from the lip, thus forming a water container from which water can overflow onto the umbrella portion; and a fence extending about the region of the element to arrest water flow to points adjacent the ice dislodging means.

6. A water distributing device for a flake ice making machine of the type in which ice dislodging means on a rotor travels about the face of a freezing cylinder to dislodge ice in flakes along an element travelling about the cylinder, the device comprising: a hub portion adapted to seat on the rotor; a conical umbrella portion extending radially outwardly and downwardly to a lip adjacent the face of the cylinder; a cylindrical wall extending about the umbrella portion at points spaced from the lip, thus forming a water container from which water can overflow onto the umbrella portion, the wall having an aperture adjacent its base to permit drainage; and a fence extending about the region of the element to arrest water flow to points adjacent the ice dislodging means.

7. In a flake ice making machine, a vertical freezing cylinder of material having relatively good heat conductivity; a supporting member of relatively low heat conductivity located below the cylinder and forming a cylindrical face contiguous with the face of the freezing cylinder; means to flow water onto the freezing cylinder to form ice thereon; a rotor having ice dislodging means operable to dislodge ice in flakes along an element travelling about the cylinder; and a blade carried by the rotor and positioned to wipe the cylindrical face of the supporting member and the adjacent face of the cylinder to remove accumulated ice crystals therefrom.

8. A flake ice making machine comprising in combination: a freezing cylinder; a rotor having ice dislodging means adapted to dislodge ice in flakes along an element travelling about the cylinder as the rotor is turned; a water distributor mounted on the rotor and comprising a conical umbrella portion extending radially outwardly and downwardly to a lip closely adjacent the face of the cylinder to define a narrow annular throat; means to distribute water over the face of the umbrella portion; and a fence extending about the region of the element to arrest water flow to points adjacent the ice

dislodging means, and releasable elements securing the distributor for rotation with the rotor.

9. A flake ice making machine comprising in combination: a freezing cylinder; a rotor having ice dislodging means adapted to dislodge ice in flakes along an element travelling about the cylinder as the rotor is turned; a water distributor mounted on the rotor and comprising a conical umbrella portion extending in gradual slope radially outwardly and downwardly to its central portions and in sharper slope radially and outwardly and downwardly to a lip closely adjacent the face; means to distribute water over the face of the umbrella portion; and a fence extending about the region of the element to arrest water flow to points adjacent the ice dislodging means.

10. A water distributing device for a flake ice making machine of the type in which ice dislodging means on a rotor travels about the face of a freezing cylinder to dislodge ice in flakes along an element travelling about the face thereof, the device comprising: a hub portion adapted to seat on the rotor; and a conical umbrella portion extending radially outwardly and downwardly to a lip adjacent the face of the cylinder, the umbrella portion having a window in the region of the ice dislodging means and a wall at the margins of the window.

11. A water distributing device for a flake ice making machine of the type wherein water is flowed onto the face of a freezing cylinder, the device comprising: a conical member having a major central portion of relatively small slope and a marginal portion of greater slope terminating adjacent the face of the freezing cylinder.

5
10

inder; and means to discharge water in rivulets on the top part of the major portion of the conical member so that it forms a continuous sheet of water before reaching the marginal portion.

12. A flake ice making machine comprising in combination: a freezing cylinder; means to dislodge ice in flakes along an element travelling about the face of the cylinder; a conical deflector mounted for rotation with the ice dislodging means and operable to deflect falling ice flakes; and a wiper fixedly positioned to traverse the face of the deflector as the deflector rotates and thereby dislodge any accumulated ice.
